UNITED STATES PATENT OFFICE.

PATRICK HARVEY, OF CHICAGO, ILLINOIS.

WATER-CLOSET.

SPECIFICATION forming part of Letters Patent No. 349,348, dated September 21, 1886.

Application filed March 18, 1886. Serial No. 193,653. (No model.)

To all whom it may concern:

Be it known that I, PATRICK HARVEY, a citizen of the United States, residing at Chicago, in the county of Cook and State of Illinois, 5 have invented certain new and useful Improvements in Water-Closets, which are fully set forth in the following specification.

The purpose of this invention is to provide a water-closet whose discharge-duct constitutes a siphon, with a simpler means than any heretofore employed for producing a vacuum, which or partial, in the siphon, by which means the same shall be "charged" and become operative as a siphon, and effect the 15 evacuation of the bowl.

It consists in providing a water-duct, which is preferably a branch of the flushing pipe or duct, but which terminates in an annular mouth within the soil-pipe encircling the discharge-limb of the siphon, whereby the air-space in the siphon above the mouth—that is to say, beyond the trap—is partially evacuated by the suction of the current of water flowing in a cylindrical or inverted conical stream past 25 the mouth of the siphon. The chief difference between this construction and others having a similar purpose is that no trap or valve is employed beyond the siphon, as is necessary when the air-space is exhausted by any means which 30 withdraws the air in a direction counter to the outflowing stream from the discharge-limb of the siphon.

In the drawings, Figure 1 is a transverse vertical section of a water-closet bowl and its discharge and flushing pipes and supply-tank. Fig. 2 is a vertical section of a detail of said structure, showing an alternative form of the adjusting device by which the annular aperture, through which the siphon-evacuating stream 40 is discharged may be regulated.

A is the bowl.

A' is the discharge-duct, of siphonic form, A¹⁰ being the receiving-limb, and A¹¹ being the discharge-limb. The trap, formed by the bowl 45 and the receiving-limb of the siphonic discharge-duct, is designated by the letter a.

B is the water-pipe from the tank or other source of supply. B' is the branch of said pipe B, which leads to the flushing-rim of the 50 bowl, and constitutes the flushing-pipe. B² is a branch of the said pipe B, which leads into the annular chamber B²⁰, which encircles the

discharge-mouth of the siphon A', and constitutes the mouth of the said pipe B².

C is the soil-pipe; c, the ventilating-duct 55 therefrom.

E is the tank; E', the service-box.

F is the supply-pipe; F', the discharge-cock, regulated in the usual manner by the float F².

G is the valve which controls the flow from the tank into the service-box, and is operated in any familiar manner. The pipe B stands up a short distance into the service-box, but has an opening or openings, b¹⁰, into it at the 65 bottom of said box; but said openings are of less total area than the mouth or cross-section of said pipe, and admit less water than can enter through the mouth. These openings serve to admit the "after-wash," the total 70 quantity of which is determined by the height to which said pipe is protruded above the bottom. The branch B² of the pipe B makes junction with said pipe by the "goose-neck" b², opening into said pipe B on the upper side of 75 the horizontal portion b. At said junction, in a suitable chamber arranged to allow it proper play, is the check-valve H, which is preferably light enough to be lifted from its seat by the water when the current fills the pipe B. Said 80 valve opens outward from the pipe B, but will be seated by any back-pressure coming through the pipe B², and is normally seated by gravity whenever the water is insufficient to keep it full—that is, when it will all be carried off 85 through pipe B².

The operation of this device is as follows: When the water is admitted to the pipe B in full volume a portion passes through B' to the flushing-rim and into the bowl, and the remainder passes by the check-valve H through the pipe B², and is discharged in a conical stream about the lower end of the discharge-limb A¹¹ of the siphonic discharge-duct A'. The action of this conical stream tends to draw 95 air with it from the said siphon, and rarefy the air therein beyond the trap a, and thereby, with the assistance of the stream entering the bowl through B' and passing out through the trap a into the discharge-limb A¹¹ of the siphon, to cause the siphon to become filled or "primed." The siphonic action of the duct A' will cause the bowl to be evacuated down to the line x x as soon as the supply of water in the

service-box falls below the mouth of the pipe B, the quantity of water passing into said pipe being limited to that which the apertures will admit, is insufficient to furnish any water to the pipe B², and the water at that instant in the siphon having passed out the siphon is "broken" by the admission of air at the line x x, and the water entering through the orifices, passing through pipe B' into the bowl, fills it up again to the original level v v. It will be noticed that to insure perfect action the pipe B should be large enough to fully supply both B' and B²; also, that pipe B² should have an area in cross-section equal to that of the annulus B²⁰, so that enough water may be admitted through said pipe B² to completely charge the annulus and form a complete and unbroken conical sheet of water discharging around the mouth of the limb A¹¹ of the siphon. The swiftness of the current of water which discharges through said annulus will affect quite materially its capacity to draw air from the siphon, and when its speed is great its quantity may be proportionately less. Its speed will depend upon the height of the service box or tank above the closet. In order, therefore, that a plumber in setting up the closet may arrange it so as to require the least quantity of water which will operate it, there is provided an adjustable mouth-piece, A¹², for the discharge-limb A¹¹ of the siphon, which may be screwed toward and from the opposed entrance into the soil-pipe C to vary the aperture through which the conical air-drawing stream is discharged. Such adjustable mouth-piece is preferably interior to the duct A¹¹, and a hand-hole closed by the cap a¹¹ is provided at the top of the siphon, through which a screw-driver may be inserted to engage the notches a¹² a¹² in the upper edge of said mouth-piece to screw it up or down. Such mouth-piece may be arranged exterior to the discharge-limb A¹¹ and interior to the annulus B²⁰ and threaded both exteriorly and interiorly, and provided with a wrench-receiving rim at the upper end, whereby it may be adjusted. Such form is illustrated in Fig. 2. In this form packing nuts and washers n and m may be employed, if found necessary, to prevent leakage about the threads; but inasmuch as the adjustment need never be changed after the closet is set, unless the pressure of the water in pipe B² is changed, said adjustable mouth-piece, once properly set and the joints leaded water-tight, will not usually require such packing. I do not claim the said adjustable mouth-piece, broadly, because I have shown and claimed the same in my application No. 180,253, filed October 14, 1885. The ventilating-pipe c should be connected into the soil-pipe as near as it can conveniently be beyond the point at which the siphon and water-duct unitedly discharge, for the reason that the air drawn from the siphon by the water-current tends to become separated from the water and to float up again into the siphon, unless it finds an earlier or easier exit.

One advantage of the method herein illustrated of withdrawing the air from the siphon from the discharge end, instead of taking it from any point higher than the upper side of the trap, (the line x x,) is that when the usual water-supply through the water-pipe from the tank is not available, so that it becomes necessary to flush the bowl by pouring water directly into it, the bowl being filled quickly up to the line y y, the level of the top of the siphon, the siphon will be filled and primed by the overflow, and the bowl will then be evacuated down to the line x x, as when the operation takes place through the usual means—the tank and connecting-pipes.

I do not claim, broadly, the use of the pipe B, protruding up into the tank and having apertures below its mouth for the purpose of furnishing two washes of different quantity to the bowl, since I am aware that such construction has been heretofore employed by others.

I claim—

1. In combination with the bowl, the siphonic evacuating-duct, and a water-pipe terminating in a chamber, which surrounds the discharge end of the siphon, said chamber and siphon both discharging into the soil-pipe, substantially as set forth. 95

2. In combination with the bowl, the siphonic evacuating-duct, a water-supply pipe having one branch discharging in the bowl and another branch terminating in a chamber, which surrounds the discharge end of the siphon, said siphon and duct both discharging into the soil-pipe, substantially as set forth. 100

3. In combination with the bowl, the siphonic evacuating-duct, a water-pipe discharging into the soil-pipe around the discharge end of the siphon, and a check-valve in such water-pipe opening with the current toward the soil-pipe and seating in the reverse direction to check back-pressure from the soil-pipe, substantially as set forth. 105

4. In combination with the bowl, its evacuating-siphon discharging in the soil-pipe, a water-pipe discharging in the soil-pipe around the discharge end of the siphon, and a ventilating-pipe leading from the soil-pipe beyond the entrance thereto of said siphon and water-pipe, substantially as set forth. 115

5. In combination with the bowl and its evacuating-siphon, a water-pipe having one branch leading to the bowl to flush the same, and another branch leading to and discharging about the end of the discharge-limb of the siphon, and a check-valve in the latter branch seating toward the said main water-pipe to cut off back-pressure from the sewer, substantially as set forth. 120

6. In combination with the bowl, the siphonic evacuating-duct, a water-pipe having one branch leading to the flushing-rim of the bowl and another branch opening out of it upward and then turning downward and discharging around the discharge end of the siphon to exhaust the air therefrom, substantially as set forth. 125 130

7. In combination with the service-box, the pipe receiving water therefrom at two levels, the apertures at the lower level being less than sufficient to supply the pipe to its full capacity, the bowl, its siphonic evacuating-duct, a branch from the water-pipe discharging into the bowl, and another branch opening out of said pipe upward and then turning downward and discharging around the discharge end of the

10 siphon to exhaust the air therefrom, substantially as set forth.

8. In combination with the bowl, its evacuating-siphon, and the service-box, the water-pipe supplied with water from the box at two levels, and insufficiently to fill it at the lower level, and having two branches, the one which is first supplied with water from the main pipe leading to the bowl, and the other, which takes

the remaining water only, discharging around the mouth of the siphon, substantially as set forth.

9. In combination with the bowl, its evacuating-siphon, a water-pipe discharging around the discharge end of the siphon, and an adjustable mouth-piece for said siphon to regulate the size of the discharge-aperture of the water-pipe, substantially as set forth.

In testimony whereof I have hereunto set my hand, in the presence of two witnesses, at Chicago, Illinois, this 26th day of February, 30 1886.

PATRICK HARVEY.
